UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

Application filed February 8, 1924. Serial No. 691,387.

To all whom it may concern:

Be it known that I, FRANKLIN R. WHITE, a citizen of the United States, and a resident of Waterbury, in the county of New Haven and State of Connecticut, have made and invented certain new and useful Improvements in Buttons, of which the following is a specification.

My invention relates to buttons of that type which are attached to cloth or other material by a metallic fastener, the actual attachment being preferably accomplished by use of an automatic button attaching machine.

The formation of buttons by a heading or swedging process from a continuous length of wire has been found to be extremely economical, in that no scrap whatever is produced, and, further, a very high rate of production may be maintained. Further, the forming of buttons by means of a header produces a very desirable button, in that it is made up entirely of one piece of metal.

In the forming of buttons by the heading process, it has been found that the best results are obtained and the most desirable button produced when a comparatively soft metal is used, such as zinc or aluminum. These soft metals, however, have heretofore required that the metallic fastener be also formed of a soft metal. It is accordingly an object of my invention to provide a button formed by the heading process wherein the fastener-receiving chamber is lined or reinforced by a hard steel anchor, so that the usual and inexpensive, although satisfactory, type of steel fastener may be used.

With the foregoing and other objects in view, my invention consists in the improved button illustrated in the accompanying drawings and hereinafter described and claimed, and in such variations and modifications thereof as will be obvious to those skilled in the art to which my invention relates, it being understood that changes may be made within the scope of what is claimed without departing from the spirit thereof.

The preferred embodiment of my invention is disclosed in the accompanying drawings, wherein:

Figure 1 is a view in longitudinal vertical section of a button embodying the characteristic features of my invention, the anchor being illustrated in elevation;

Figure 2 is a similar view illustrating the button attached to a cloth or other material by means of the metallic fastener;

Figure 3 is a bottom plan view of the finished button;

Figure 4 is a view in vertical section of a button having a somewhat modified form of anchor or steel lining; and

Figure 5 is a view in elevation of this latter form of anchor.

Referring specifically to the several views, wherein similar reference numerals designate corresponding parts throughout, my improved button is composed of a head 11 from which, as illustrated in Figure 1, projects the integral hub forming portion 12. This hub forming portion 12 is illustrated in Figure 1 and as produced by a heading machine is provided with a cylindrical chamber 13 therein of approximately straight walls 75 and in which is placed the steel anchor or die 14. The lower extremity 15 of the die or anchor is of restricted diameter, so that the hub forming portion 12 may be swedged or compressed inwardly to form the hub 16, as 80 illustrated in Figure 2. The swedging of the hub forming portion 12 causes the metal of the lower portion to flow partially across the lower extremity of the anchor as at 17, which metal, together with the tapering formation of the die or anchor itself and the tapering walls of a completed hub, securely locks and binds the anchor in place. The anchor includes the customary restricted throat 18 and the enlarged fastener-receiving chamber 19. This anchor thereby provides a hard metal or steel lining for the interior walls of the hub or fastener-receiving chamber. Thus I am able to provide a button formed by the heading process and com- 85

posed of soft and readily workable metal such as zinc or aluminum, or some alloy, and to fasten the button to the garment by means of a steel or hard metal tack which insures the permanency of the fastening of the button to the garment.

A somewhat modified form of my invention is disclosed in Figures 4 and 5, wherein the hollow hub 20 is provided with a steel or hard metal anchor 21, the latter being 105 provided with the substantially straight or cylindrical side walls 22. The metal of the hub 20 has been flowed beneath the bottom of the anchor as at 23, thus securely locking the anchor in place. The anchor is in this 110

instance provided with an upturned flange 24 adjacent the opening extending therein, so that as the steel fastener 25 is forcibly driven into the anchor the end 26 of the fastener will be overturned and brought down against and behind the rim 24 and thereby permanently locking the two together.

While I am aware that it is not new to provide a steel anchor in connection with a button made up of several parts, as I have been producing buttons by this method for a great many years, yet I do believe it to be new and original with me to provide a button produced by the heading process and formed of soft metal and to reinforce and line the hollow hub thereof with steel walls so that a metal fastener may be used which is formed of material considerably harder than that of which the body of the button is formed and I accordingly claim the following to be new and original with me:

1. A button formed of comparatively soft metal and comprising a one-piece head and hub, the said hub provided with a chamber

therein having an opening leading thereto, 25 an anchor formed of comparatively hard metal located within said chamber and provided with an opening aligning with the opening leading into the said hub, said anchor provided with an enlarged fastener-receiving recess, the side walls of said hub compressed against the side walls of said anchor and holding the same in place.

2. A button formed of comparatively soft metal comprising a one-piece head and hollow hub, an anchor formed of comparatively hard metal located within said hollow hub the walls of said hub tapering toward their lower extremity and compressed against the walls of the anchor and permanently locking 40 the same in place.

Signed at Waterbury in the county of New Haven and State of Connecticut this 6th day of February A. D. 1924.

FRANKLIN R. WHITE.
